UNITED STATES PATENT OFFICE.

CARL ALBERT HIRTH, OF CANNSTATT, STUTTGART, GERMANY.

KNIFE FOR LEATHER-SKIVING MACHINES.

1,117,381.

Specification of Letters Patent. Patented Nov. 17, 1914.

Application filed April 29, 1911. Serial No. 624,213.

To all whom it may concern:

Be it known that I, CARL ALBERT HIRTH, a subject of the German Emperor, residing at Cannstatt, Stuttgart, Germany, have invented a certain new and useful Improved Knife for Leather-Skiving Machines, of which the following is a specification.

This invention relates to an improved knife for leather skiving and like machines of the cylindrical type which is used in leather skiving, beveling, and splitting machines.

The present invention has for its object to produce a cutting knife of a simple character possessing great resistance and cutting power and an increased working life, while at the same time it is specially formed so as to insure its being truly mounted upon the carrier shaft both as regards being at right angles thereto and central thereon, so that it will revolve with a perfectly true running cutting edge.

To this end the improved knife is formed so that it has in combination two features, viz:—It is formed out of one piece of material, that is to say, the cylindrical portion, which has inner and outer concentric cylindrical walls for a part of its length, and the end disk, which is thicker than the cylindrical portion between said inner and outer walls, are formed integrally of one and the same piece of metal, which is turned, hardened, ground and finished and consequently must retain its form, having no internal strains, the front or edge of the overhanging rim of the cylindrical portion being sharpened in the usual manner; and on the disk or flattened portion of the knife a central hole is made and a raised surface is provided into which a series of holes are pierced to enable the knife to be fastened to the end of the shaft in the skiving machine in a manner which is usual.

Referring to the annexed drawing, which is a section through the center of the knife, *c* is the cutting edge, *b* the cylindrical or overhanging rim or surface provided for wear, *a* is the thickened disk on which is a raised surface *e* ground truly at right angles to the cylindrical portion of the knife and *d* is the central hole also ground truly to insure the knife being mounted centrally on the carrying shaft.

It will be seen from the foregoing and

with reference to the drawing that the great 55 resistance and extreme lightness of the knife is caused by the cylindrical portion *b* being connected to the disk portion *a* through the rounding of the metal connecting the disk to the cylinder and it will also be clear for 60 the same reason that the cylindrical portion may be of considerably increased length, giving approximately one-fifth longer life than a knife of the usual length and construction, while at the same time the knife 65 may be mounted on its shaft with great accuracy seeing that the ground hole *d* will fit upon the shaft to exactly centralize the knife, and the ground raised surface *e* by being firmly bolted or screwed up to the 70 flange or shoulder on the shaft through the holes *f*, will keep the knife at right angles to the shaft.

I am aware that it is not new to form a cutting knife, of the kind herein described, 75 out of one piece of material, and I do not claim this feature except in combination with the other herein described features for truly mounting the knife upon its shaft, and further, I am aware that similar means to 80 the last mentioned features for truly mounting the knife have been provided on similar cutting knives, but such knives have not been made in one piece of material.

What I claim is:—

The herein described knife for a leather skiving machine comprising a body of cylindrical form in cross section having inner and outer concentric cylindrical walls with a cutting edge at one end, and provided at 90 its other end with an integral head of greater thickness throughout than the body, said head having a central portion of increased thickness with parallel walls provided with an aperture concentric with the 95 knife body to receive a support for the knife, and accurately center the knife on such support, and a plurality of apertures *f* to receive fastening devices for securing the knife to its support.

In testimony whereof I have hereunto set my hand in the presence of two subscribing witnesses.

CARL ALBERT HIRTH.

Witnesses:

ERNEST ENTENMANN,
FRIDA KLAIBER.
